(57) **CLAIM**

The ornamental design for a shuttle vehicle, as shown and described.

DESCRIPTION

FIG. 1 is a front view of a shuttle vehicle showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a partial enlarged view of FIG. 3.

The area within the broken lines comprises structure or features of the shuttle vehicle that form no part of the claimed design.

The dot-dash broken lines identify an area of enlargement.

1 Claim, 7 Drawing Sheets
